UNITED STATES PATENT OFFICE.

CHARLES ROSECRANS, OF PHILADELPHIA, PENNSYLVANIA.

BEVELING-TOOL.

SPECIFICATION forming part of Letters Patent No. 730,163, dated June 2, 1903.

Application filed November 18, 1902. Serial No. 131,902. (No model.)

To all whom it may concern:

Be it known that I, CHARLES ROSECRANS, a citizen of the United States, residing at Philadelphia, in the county of Philadelphia and State of Pennsylvania, have invented 5 certain new and useful Improvements in Beveling-Tools; and I do hereby declare the following to be a full, clear, and exact description of the invention, such as will enable others skilled in the art to which it appertains to make and use the same.

This invention relates to improvements in beveling-tools.

The object of the present invention is to 15 improve the construction of harness-makers' beveling-tools and to provide a simple, inexpensive, and efficient one which will be positive and reliable in operation and in which the tool is more especially adapted for the 20 purpose of beveling or trimming the edge of apertures formed in leather.

Another object is to construct a tool which will bevel the edge of any kind of an aperture in leather.

25 The invention consists in the novel arrangement and construction of parts, as are herein-after fully described, illustrated in the accompanying drawings, and pointed out in the claims appended hereto.

30 In the accompanying drawings, Figure 1 represents a perspective view of my improved tool. Fig. 2 is a plan view of the shank, having the beveling cutting-surfaces formed upon the hooked end thereof. Fig. 3 is a horizontal cross-sectional view of the same.

35 Like numerals of reference indicate corresponding parts in all the figures of the drawings.

1 designates a suitable handle, and 2 is the 40 shank secured thereto. The said shank 2 has a hooked end 3, and an aperture is formed at the point of its bend. Beveling concaved cutting-surfaces 4 are provided upon the hooked end. 5 are the guiding edges of the 45 hooked end, said edges forming a gage for the tool. The inner edges thereof are beveled inwardly toward the aperture formed in the hooked end. A groove is formed upon the hook 3 and also on the shank 2 and terminates in the cutting-surfaces 4.

50 In operation a uniform beveled edge is obtained by the use of either of the cutting-sur-

faces. It will be seen that the guiding edges will bear against the side of the leather and will not permit of the cutting-surface sinking 55 into the same farther than a uniform depth. Therefore the hooked end has a great advantage in forming a tool of this character, for a gage is formed integral therewith, and the beveling concaved cutting-surfaces which are 60 formed thereon permit of a quick and efficient operation.

Changes in the form, proportion, and minor details of construction may be resorted to without departing from the spirit or sacrificing 65 any of the advantages of the invention.

Having thus fully described my invention, what I claim as new, and desire to secure by Letters Patent, is—

1. A device of the character described, comprising a suitable shank, and opposite cutting surfaces thereon spaced apart an equal distance to their length forming a gage, substantially as described. 70

2. A device of the character described, comprising a suitable shank hooked or folded at its end upon itself and provided with a concave aperture in the point of the bend, forming oppositely-arranged cutting edges extending in the same direction, substantially 75 80 as described.

3. A device of the character described, comprising a suitable shank, and cutting-surfaces thereon spaced apart a distance equal to their length, substantially as described. 85

4. A device of the character described, comprising a suitable shank, and a hooked end formed thereon apertured at the point of its bend and beveled inwardly toward said aperture, substantially as described. 90

5. A device of the character described, comprising a handle, a shank secured thereto, a hook formed at its free end, double cutting-surfaces formed between said cutting-surfaces and thereon, and a gage formed integral therewith, substantially as described. 95

6. A device of the character described, comprising a handle, a shank secured thereto having a hooked end, double cutting-surfaces formed on said end, and a guide formed at 100 either side of the cutting-surface, substantially as described.

7. A device of the character described, comprising a handle, a shank secured thereto

having a hooked end, opposite cutting-surfaces formed on said end, and means limiting the cutting capacity of said surfaces formed between and integral therewith, substantially as described.

8. A device of the character described, comprising a handle, a shank secured thereto having a hooked end, and opposite concaved cutting-surfaces formed thereon, substantially as described.

9. A device of the character described, comprising a suitable shank, a hook formed thereon having a concave aperture at the point of its bend, and grooves upon said hooked end for guiding the cutting-surfaces formed by the said aperture, substantially as described.

10. A device of the character described,

comprising a suitable shank, a hook formed thereon at its free end and provided with a concave aperture, said concavity being arranged transversely of the shank, substantially as described.

11. A device of the character described, comprising a shank, a hook formed thereon having at the point of its bend an aperture extending in the direction of the bend, and two grooves formed upon the said hooked end for guiding the cutting-surfaces formed by said aperture, substantially as described.

In testimony whereof I hereunto affix my signature in presence of two witnesses.

CHARLES ROSECRANS.
